ELECTRIC WALL PLATE

Henry C. Lovine, Naugatuck, Conn.

Application April 5, 1954, Serial No. 29,857

Term of patent 14 years

(Cl. D26—13)

Fig. 2

Fig. 3

To all whom it may concern:

Be it known that I, Henry C. Lovine, have invented a new, original, and ornamental Design for an Electric Wall Plate, of which the following is a specification, reference being had to the accompanying drawing, forming a part hereof.

Fig. 1 is a top plan view of an electric wall plate showing my new design.

Fig. 2 is a cross sectional view of the same, taken along the line 2—2 of Fig. 1 looking to the right.

Fig. 3 is a cross sectional view of the same, taken along the line 3—3 of Fig. 1, looking to the left.

I claim:

The ornamental design for an electric wall plate, substantially as shown.
